FRONT OPENING WATCH DISPLAY BOX

Francis E. Blod, Tuckahoe, N. Y., and Alfred M. Blumenfeld, Hackensack, N. J., assignors to The Gruen Watch Company, Cincinnati, Ohio, a corporation of Ohio

Application September 21, 1950, Serial No. 186,072

3 Claims. (Cl. 206—45.13)

1

This invention relates to boxes designed for the display of watches, jewelry and the like and is particularly concerned with a novel structure for the display of curved back watches in which a new mechanical arrangement provides an extremely effective display of the merchandise.

Boxes, of the type to which this invention relates, are extensively used in retail stores for the display of watches and other items of jewelry either in a show-case or in a display window. In a box of this type the watch strap is fastened over a watch holder which supports the case and band. It is desirable from the sales viewpoint that when being displayed the watch and strap are arranged so that they look as if they were being worn. Also in order that the customer may more closely inspect the watch and strap it is desirable that the holder be easily removed from the box. Since these boxes also serve as a storage place for the merchandise after it has been sold and delivered to the customer it is necessary that they be of a durable construction. It is a well recognized fact in the trade that the attractiveness of the package and novelty and effectiveness of the display are extremely important sales factors for this type of merchandise. It is essential therefore that the display boxes be of attractive appearance both on the exterior and interior and it is equally important that the boxes provide an effective display of the merchandise.

Previous attempts have been made to provide boxes combining these desiderata but none have succeeded in combining all of them. Boxes have been provided with an elevatable tray which is automatically positioned when the box is opened. However, these boxes display the watch and strap mounted horizontally on a flat card, thus losing much of the effectiveness of the display because the strap does not have the appearance of being placed upon a wrist and furthermore the watch face is rotated 90° from the direction in which it is normally viewed making it difficult to read the numerals, and so forth. Other boxes have been provided in which the watch and strap are displayed in a vertical plane. These do not have the advantages of the elevatable holder which can be readily removed to permit inspection of the watch. Display boxes of the type disclosed in this application fill a long existent need in the jewelry field since they are free from the limitations inherent in the previous display means.

An object of this invention is to provide a display box in which the strap of the watch being

2

displayed is fastened around the watch holder in a vertical plane, thus allowing the watch face to be viewed in its normal position.

An additional object of this invention is to provide a display box in which the watch or jewelry being displayed is so positioned that the watch face or principal ornamentation is presented in the fullest view and the strap or band is supported so as to simulate the appearance of being worn.

A further object of this invention is to provide a box in which a novel mechanical arrangement operates to automatically align the merchandise in the desired display position as the box is opened.

Another object is to provide means for automatically positioning the merchandise on display which means are compact and simple, requiring a minimum of parts, yet are dependable in operation.

A further object is to provide a display box adapted for storage and display of watches, jewelry and the like which has an attractive and unusual appearance both when the box is closed and when it is open.

Another object is to provide a display box particularly for curved wrist-watches in which the watch with its associated band is adapted to be displayed on a watch holder which can be readily inserted in or removed from the box without detaching the watch from the holder.

Other objects and advantages will be apparent from the detailed description of the invention when considered in conjunction with the drawings in which:

Figure 1 is an end elevation of the box in the closed position.

Figure 2 is an end elevation view of the box in the open or display position.

Figure 3 is a front elevation of the same box.

Figure 4 is a fragmentary sectional view of the box in the open position showing the watch holder in elevation and the base and drop shells in section.

Figure 5 is a fragmentary sectional view of the drop shell illustrating details of its construction not shown in Figure 4.

Figure 6 is a longitudinal sectional view of the watch holder taken along the line 6—6 of Figure 4.

Figure 7 is a transverse cross-sectional view of the watch holder taken along line 7—7 of Figure 6.

Figure 8 is a top plan view of the shaft before assembly.

As shown in Figures 2 and 3, this invention essentially comprises a display box having a base shell 10, a drop shell 11, and a watch holder 12. The base shell 10 is provided with a flat portion 13 making it adaptable to stand upon a flat surface such as a shelf or display counter. The base shell 10 and drop shell 11 are hingedly mounted with respect to each other by means of ball bearings 14 engaged in the bearing pivots 15 interposed between the adjacent portions of the two shells. The watch holder 12 upon which the watch is displayed is rotatably mounted within the drop shell 11.

The detailed construction of a typical embodiment of my invention is best shown in Figures 4 through 8.

The watch holder 12 is generally elliptical in cross section, with one of the ends 16 of the ellipse being somewhat flattened in order to more closely conform to the contour of the watch case, which is placed over it.

When displaying the watch, the strap is secured around the periphery of the watch holder so that the watch case is held firmly against the flattened end 16 of the holder 12 and the strap is supported so that it has the appearance of being worn on a wrist.

The watch holder 12 is further provided with a slot 17 running longitudinally through it at a point removed from the flattened portion supporting the watch case. Bearing shoulders 18 are provided around the periphery of the slot. These bearing shoulders 18 engage the shaft 19 between the stop shoulders 20 on the shaft which are adapted to prevent any transverse movement of the watch holder. At each end of the shaft teardrop lugs 21 extend perpendicular to it. These lugs 21 are adapted to engage in the sockets 22 (Figure 5) projecting inwardly from each end of the drop shell 11.

The configuration of these lugs 21 and the sockets 22 into which they are fitted prevents any rotation of the shaft 19 with respect to the drop shell. It does however, permit the shaft 19 to be readily lifted from engagement with the drop shell 11 when it is desired to remove the watch holder 12 from the box.

The shaft 19 is assembled from two end lugs 21, an aligning bar 23, and two wedge plates 24. The aligning bar 23, of rectangular cross section, has a projecting head 25 extending longitudinally along its upper edge. During assembly this bar 23 is first secured to the interior of one of the lugs 21 and is then inserted through the slot 17 in the watch holder until the stop shoulder 20 abuts the edge of the bearing surface 18 of the watch holder 12. The other lug 21, having two wedge plates 24 secured to it, is then inserted in the slot 17 from the other end and over the aligning bar 23 in such a manner that the wedge plates engage the bar 23 upon opposite sides. The bar and wedge plates are secured by some adhesive means to complete the shaft assembly.

The interior of the watch holder 12 is provided with a flange 26 having a slot 27 adapted to receive the loop or bent end of the aligning spring 28. This spring 28 consists of a piece of spring wire or strip of spring metal bent in the middle so as to form a narrow elongated U having a small loop at the bent end and a collar 29 slidably fitted over the spring to permit the adjustment of the tension between its open ends. The open ends of the spring are adapted to be fitted over the aligning bar 23 of the shaft which turns between the two ends as the watch holder 12 rotates about

the shaft 19. The action of the spring 28 is such that it tends to align the axis of the spring, and hence the watch holder 12, with the position assumed by the aligning bar 23 as shown in Figure 7.

In operation after the watch has been fastened over the watch holder 12, the holder is placed in the drop shell 11 by inserting the lugs 21 in the sockets 22 provided. The position of the shaft 19 is thus fixed in that it cannot rotate with respect to the drop shell 11. The direction in which the shaft aligning bar 23 is pointed is also fixed as the bar is permanently secured to the end lugs 21 of the shaft. The position assumed by the aligning bar 23 in turn determines the position of the watch holder 12 since the action of the spring 28 riding over the aligning bar 23 is such that the axis of the spring 28 tends to coincide with the direction taken by the aligning bar 23. Thus with the box open, the watch holder 12 is supported by the spring 28 riding on the aligning bar, at a pre-determined angle to the base shell 10. The watch face mounted upon the flattened end 16 of the watch holder is accordingly held in the most advantageous position for display.

As the box is closed the drop shell 11 rotates about the bearings 15 causing the shaft 19 to turn with it. The watch holder 12 is caused to rotate until it comes in contact with the rear surface 30 of the base shell 10. Further rotation of the watch holder 12 is then prevented. However, the drop shell 11 can be further closed since the shaft 19 can be rotated with respect to the watch holder 12 if enough force is applied to cause the aligning bar 23 to spread apart the open ends of the aligning spring 28. After the drop shell 11 has been rotated into the closed position it is held there by the action of the lip 31 engaging the groove 32 in the base shell 10. When the box is opened the reverse action takes place. The drop shell 11 is rotated downwardly about the bearings 15 causing the shaft 19 to rotate with it. Under the tendency of the spring 28 to become aligned with the direction taken by the aligning bar 22 the watch holder 12 also rotates downwardly until the drop shell has opened to its extreme position. With the box open the watch holder 12 is supported by the spring in its angulated display position.

The base shell 10 and drop shell are preferably formed from a plastic which provides an exceptionally pleasing exterior appearance. The interior preferably includes a lining which presents a soft background for the merchandise and conceals any irregularities in the interior surface of the shells. The watch holder periphery also is preferably lined to enhance the attractiveness of the display.

The construction is of an extremely simple nature comprising plastic parts which may be readily molded, standard ball bearings and an easily formed spring. Such a box is extremely well adapted for use by retail jewelers since the watch may be pre-fastened to the holder and the holder in turn may be quickly and easily removed from or inserted into a box, thus providing not only an effective display but a simple means for handling the merchandise for inspection by the customer.

Having described my invention, I claim:

1. A display box for watches and the like comprising a base shell, a drop shell, said shells being hingedly interconnected, sockets projecting inwardly from said drop shell, a shaft, said shaft

including a lug extending from each end thereof and an aligning bar disposed intermediate said lugs, said lugs residing within said sockets and being confined within said sockets to prevent rotation of said lugs relative to said sockets, a watch holder, said watch holder being rotatably mounted upon said shaft, said aligning bar having a body of substantially rectangular cross section and a projecting head extending longitudinally at its upper edge said aligning bar being disposed so that its head and body are angularly oriented relative to said drop shell, a spring of generally U-shaped configuration, the closed end of said spring being rigidly secured to said watch holder, the other end of said spring embracing said aligning bar and engaging the head and body thereof, whereby the spring is effective to urge the watch holder into a display position in which the watch holder is angularly disposed with respect to said drop shell.

2. A display box for watches and the like comprising a base shell, a drop shell, said shells being pivotally interconnected, a shaft, a watch holder rotatably supported on said shaft, mounting means associated with one of said shells, said shaft being confined within said mounting means to prevent rotation of the shaft relative thereto, said shaft including an aligning bar having a portion of substantially rectangular cross section and a projecting head at its upper edge said shaft being supported in said mounting means so that the head and rectangular portion of said aligning bar extend angularly relative to the shell associated with said mounting means, a spring of generally U-shaped configuration, said spring being rigidly secured to said watch holder, the open end of said spring embracing said aligning bar and being effective to urge said watch holder toward a display position in which said watch holder is angularly disposed with respect to the

shell having the mounting means associated therewith.

3. A display box for watches and the like comprising a base shell, a drop shell, said shells being hingedly interconnected, sockets projecting inwardly from said drop shell, a shaft, said shaft including a lug extending from each end thereof and an aligning bar disposed intermediate said lugs, said lugs being confined within said sockets to prevent rotation of the lugs relative to said sockets, said lugs being insertable and removable from said sockets by slideable movement relative thereto, a watch holder, said watch holder being rotatably mounted upon said shaft, said aligning bar having a body of substantially rectangular cross section and a projecting head extending longitudinally at its upper edge said aligning bar being disposed so that its head and body are angularly oriented relative to said drop shell, a spring of generally U-shaped configuration, the closed end of said spring being rigidly secured to said watch holder, the other end of said spring embracing said aligning bar and engaging the head and body thereof, whereby the spring is effective to urge the watch holder into a display position in which the watch holder is angularly disposed with respect to said drop shell.

FRANCIS E. BLOD.
